UNITED STATES PATENT OFFICE.

MIKE TELESZKY, OF JENNERS, PENNSYLVANIA.

GUARD FOR CALENDER-MACHINES.

1,251,840.

Specification of Letters Patent.

Patented Jan. 1, 1918.

Application filed September 5, 1917. Serial No. 189,773.

To all whom it may concern:

Be it known that I, MIKE TELESZKY, a subject of the King of Hungary, residing at Jenners, in the county of Somerset and State 5 of Pennsylvania, have invented certain new and useful Improvements in Guards for Calender-Machines, of which the following is a specification.

This invention relates to certain new and 10 useful improvements in guards for calender machines.

The primary object of the present invention relates to the provision of a guard associated with the rolls of a calendering or paper making machine whereby injury to the operator in manipulating the paper about the rolls will be prevented.

A further object of the invention is to provide an adjustable mount for the guard that 20 is capable of adjustment to and from the rolls and also capable of verifying height thereof relative to the rolls.

The invention also contemplates functioning as a doctor in stripping the rolls of pulp wound thereon, such an operation being 25 readily understood.

With the above general objects in view and others that will appear as the nature of the invention is better understood, the same 30 consists in the novel construction, combination and arrangement of parts hereinafter more fully described, illustrated in the accompanying drawing and then claimed.

In the drawing forming a part of this application and in which like designating characters refer to corresponding parts throughout the several views,

Figure 1 is a vertical cross sectional view 40 of a calender or similar paper making machine provided with the present protective device operatively arranged relative thereto.

Fig. 2 is a front elevational view of a portion of one of the rolls and a portion of one of the guards.

Fig. 3 is a horizontal sectional view showing the adjustable bracket arms for supporting the guards and

Fig. 4 is a detail perspective view of one of the adjustable bracket arms.

In paper making machines of the type 50 herein disclosed, there is provided a series of vertical aligned rolls between which the paper pulp is adapted to travel, the rolls being preferably arranged in pairs in that 55 the rotation of each pair of rolls is opposite to each other. In manipulating the paper

passing between these rolls, the operators are liable to injury by having the hands caught and mashed between the adjacent rolls, and with the object in view of preventing this, a particular form of guard and mount therefor is provided whereby the operator's hands will be prevented from passing so close to the rolls as to cause injury thereto.

Referring more in detail to the accompanying drawing, there is provided a base 5 of any standard form of paper making or calendering machine having upright spaced parallel frame members 6 between which the successive rollers 7 are journaled at their ends.

The improved form of guard comprises in detail, socket members 8 carried by the machine base 5 and having received therein vertical standards 9 upon which at varied heights, the adjustable brackets 10 for supporting the guards 11 are adjustably secured. Each bracket 10 is formed of two parts 12 and 13, the part 12 having an opening therein whereby the said part is slidably received on the vertical standard 9 and adjustably secured in position by the thumb screw 14. As illustrated in Figs. 3 and 4, the bracket portion 13 is provided with an elongated slot 15 through which a bolt 16 carried by the bracket part 12 is adapted to be projected and retained in the desired position in said slot by the nut 17 upon the threaded end thereof. A recess 18 is formed 90 in the outer end of the bracket part 13 and is adapted to receive the end extension 19 of the guard plate 11, the guard plate 11 being of angle construction and having a substantial knife edge 20 bearing with the 95 desired tension upon the adjacent roll 7. As shown in Figs. 3 and 4 the rear angle edge extension 19 is received in the slot 18 and the lug 21 carried by the end of said bracket arm 13 will engage the end edge 22 of the guard plate 11, thereby to hold the guard plate in proper position, it being noted that one of the brackets 10 is positioned at each end of the guard plate 11.

From the above detailed description of 105 the invention it is thought that the construction and operation of the invention will be readily apparent, it being noted that the desired relative positions between the rolls 7 and guard plates 11 may be obtained by 110 adjusting the screw 16 in the slot 15 of the bracket part 13 and also regulating the

height of the bracket upon the vertical standards 9.

While I have shown and described the preferable embodiment of the invention, it will be understood that various changes may be made in the details of construction thereof without departing from the spirit and scope of the invention as claimed.

What I claim as new is:—

- 10 1. A guard for paper making machines comprising vertical standards, brackets adjustably secured thereto, each bracket including two parts, a bolt carried by one part, the other part being slotted for the adjustable reception of said bolt, a recess formed in the outer end of the slotted part, and an angle guard plate having an end
- 15

extension on its vertical wall received in said socket with the end of the horizontal wall thereof adapted for engagement with 20 the end of the slotted part.

2. A guard for paper making machines comprising vertical standards, brackets adjustably secured thereto, each bracket including two parts, a bolt carried by one part, 25 the other part being slotted for the adjustable reception of said bolt, a recess formed in the outer end of one of said parts, and an angle guard plate having an end extension received in said socket with the end of 30 the other wall thereof adapted for engagement with the end of the slotted part.

In testimony whereof I affix my signature.

MIKE TELESZKY.
